CONTAINER AND LOCK-COVER THEREFOR

Louis Eisenman, Brooklyn, N. Y.

Application August 23, 1935, Serial No. 37,582

9 Claims. (Cl. 220—56)

This invention relates to improvements in containers having covers or closures, together with means for holding or locking the closures in place. The invention will be described hereinafter more particularly with relation to its application to well known trash or garbage cans, in which it is highly desirable that the cover or closure be held securely in place against accidental removal.

10 One of the objects of the present invention is to provide a container of the above general character preferably constructed of sheet metal and having the usual sheet metal cover, together with simple and practical means directly associated 15 with the handle or bail cooperating with these parts for securely and efficiently holding the cover in place.

A further object of the invention is to provide a device of the above character, having relatively few parts, which may be inexpensively manufactured and assembled.

20 A further object is to provide a device of the above character, in which the parts may be easily operated and the cover, together with the bail, removed from the container if and when desired, as for cleaning.

25 A further object is to provide a container of the above character provided with a friction lock, as well as a positive lock, each cooperating with the other thereby more efficiently to hold the cover in place against accidental removal yet permit ready removal for emptying the container.

Other objects will be in part obvious from the annexed drawing and in part hereinafter indicated in connection therewith by the following analysis of this invention.

This invention accordingly consists in the features of construction, combination of parts, and in the unique relation of the members and in 40 the relatively proportioning and disposition thereof, all as more completely outlined herein.

To enable others skilled in the art to comprehend fully the underlying features of this invention, that they may embody the same by the 45 numerous modifications in structure and relation contemplated thereby, a drawing depicting one form of the various possible forms of the invention has been annexed as part of this disclosure, and in such drawing like characters of reference denote corresponding parts throughout all of the views, in which—

Fig. 1 is a side elevation of the complete container and cover in assembled relation, the handle being shown also in dotted lines in one of its 50 other various positions.

Fig. 2 is a detail side elevational view of one of the securing means.

Fig. 3 is a detail sectional view along line 3—3, Fig. 2.

Fig. 4 is a detail perspective view of certain 5 parts of the handle on the cover.

Fig. 5 is a detail view of one of the guide members associated with the closure for the container.

Referring now to the drawing in detail, and 10 more particularly to Fig. 1, 10 indicates a container which in the present form illustrates the usual well known cylindrical garbage or trash bucket. This is provided with a cover having a substantially flat top 11, an outwardly flared portion 12 adapted to rest on the top of the container, and a downwardly extending flange 13 surrounding the top and side of the container for approximately one inch down. The cover is provided with a handle member 14 as shown more 15 clearly in Fig. 4, which includes the top or main handle portion, the two verticals 15, and the laterally extending ears 16 which are adapted to be riveted or otherwise permanently secured to the relatively flat portion 11 of the cover.

This handle, including the parts 14 and 15, is 20 preferably of channel form, that is, each part 15 is provided with inwardly extending flanges 17 and the part 14 with downwardly extending side flanges 18. Movable mounted within this 25 enclosed portion is an auxiliary handle 20 of channel form or provided with upwardly extending flanges 21 adapted to slide or be guided between the two flanges 17 on the uprights 15. Interposed between the two flanged portions 14 30 and 20 is a spring member 22, preferably in the form of a flat steel strip bent back upon itself in substantially the manner shown in Fig. 1 and 35 permanently secured in any desired manner at its ends to the under surface of the part 14 and the upper surface of the part 20. Such construction provides for relative movement of the parts 14 and 20 towards and from each other for 40 reasons which will be hereinafter more fully explained.

45 From Fig. 4 it will be seen that the end members 15 are slotted as indicated at 23 and through one of these slots extends an anchoring member 24, Fig. 1, connected by means of a resilient and flexible member 25 with a laterally movable latch member 26 carried in a housing 27. Thus as the auxiliary handle 20 moves upwardly with respect to the member 14, the flexible connection withdraws the latch member 26 from its engagement with a notch 28 in the handle or bail 30. Con- 50

55

sequently, when the parts are shown in the position illustrated in Fig. 1, the bail or handle 30 rests upon the top of the cover handle 14, thus holding the cover securely in place upon the container and positively preventing its accidental removal. By grasping the handle portion 14 and 20 and squeezing the same, the latch 26 may be withdrawn from the notch 28 whereupon the bail 30 may be raised to the dotted line position and, 10 as the bail and handle member 14 are usually grasped simultaneously, the cover 11 may be readily removed from the container in one operation. In other words, an upward pull by inserting the fingers immediately below the handle portion indicated at 14 will cause the cover and bail to move together.

It will be noted that the vertical portions of the bail 30 pass through U-shaped guide members 31 shown more clearly in Fig. 5. These guide members are secured in any desired manner as by means of rivets 32 to the side portions of the cover 11 as shown in Fig. 1. The lower ends of the bail 30 are bent outwardly and each carries a roller 33 as shown more clearly in Fig. 2. This 25 roller is riveted to the bent-over end of the bail 30 as indicated at 34 and travels vertically in a tubular shell 35 having a rectangular cross-section as indicated in Fig. 3. A vertical groove 36 at one side accommodates the handle while the 30 housing 35 accommodates the roller 33. A removable plate 37 is adapted to be slipped into guide grooves 39, Fig. 3, and the housing is provided with laterally extending ears 38 which are secured in any desired manner by means of rivets 40 to the container 10.

It will be noted that the upper parts of the sides of the housing 35, Fig. 2, are bent inwardly as indicated at 41 thereby to prevent the roller 33 from pulling out of the top of the casing and 40 at the same time permit a free swinging of the bail to either side. However, the plate 36 terminates just short of the topmost position of the roller 33 whereby the roller may be moved laterally inwardly against the natural resiliency 45 of the bail 30 and then slipped out of the rear top of the housing 35 as will be apparent from Fig. 3.

It will further be noted that the downwardly extending side walls of the housing 35 as shown 50 in Fig. 2 taper very slightly inwardly. Thus when the roller 33 is in its topmost position there is clearance of several thousandths of an inch on each side, but when depressed to the lowermost or dotted line position as shown in Fig. 2, then 55 this roller 33 wedges between the sides of the housing 35 and thereby provides a substantial friction lock. When in this position the latch 26 coats with the notch 28 at the inner side of the bail if depressed, but when in the topmost position then the latch engages a second notch 42 as indicated in Fig. 1. Thus it will be seen that 60 the cover can be positively locked in two positions of the bail, that is, either in its upper or lower position, and can be additionally frictionally locked when the bail is in its lowermost position. Likewise the cover may be locked in operative relation to the bail when sealing the container or when removed from the container on the upward movement of the bail. This has certain marked advantages inasmuch as that when 65 the cover is raised upwardly with the bail, the cover and bail may be swung together laterally to either side thereby facilitating in the emptying of the container.

70 The operation of the above described device will

be obvious to those skilled in the art. It may be stated, however, that when it is desired to close the container and lock the same in position then the cover 11 is placed over the top of the bucket 10 and the bail forcibly pressed down to the position shown in full lines in Fig. 1. The bail holds the cover in place and is frictionally locked by the rollers which are then in their lowermost position within the housing 35. When it is desired to remove the cover, the two parts of the 10 handle shown in Fig. 4 are squeezed together and moved relatively upwardly, thus withdrawing the rollers 33 from their frictional engagement with the side walls of the housing 35 and, when the rollers reach their topmost position as 15 shown in Fig. 2, the bail with the cover may be turned to one side or the other of the container as desired, thereby permitting easy removal of the contents. The bail and cover are then swung back to a position above the bucket and the cover, 20 either with or without the handle, depressed to covering position. If the cover is depressed alone, then the notch 42 at the end of the bail will be in position to receive the latch member 26 and thereby positively lock the cover upon the container. 25

It is thus seen that the present invention contemplates a simple and practical device well adapted to accomplish, among others, all of the objects and advantages herein set forth. 30

Without further analysis the foregoing will so fully reveal the gist of this invention that others can, by applying current knowledge, readily adapt it for various applications without omitting certain features that, from the standpoint of the prior art, fairly constitute essential characteristics of the generic or specific aspects of this invention and, therefore, such adaptations should and are intended to be comprehended within the meaning and range of equivalency of the following claims. 35

I claim:

1. A locking closure for containers having a pivotally mounted movable bail, guide members mounted on the sides of the container in which the ends of the bail are adapted to move, said guide members being wedge-shaped whereby when the bail is depressed the lower ends thereof have a wedging locking engagement thereby to hold the closure on the container. 50

2. A locking closure for containers having a pivotally mounted bail, rollers at the lower ends of the bail, locking members including wedge-shaped guides at the sides of the container adapted to receive the rollers on the ends of said bail and to frictionally grip the rollers and hold the bail in depressed position, thereby retaining the cover in locked position upon the container. 55

3. A locking closure for containers having a pivotally mounted bail, rollers at the lower ends of the bail, locking members including wedge-shaped guides at the sides of the container adapted to receive the rollers on the ends of said bail and to frictionally grip the rollers and hold the bail in depressed position, thereby retaining the cover in locked position upon the container, and a positive locking means carried by the cover of the container engaging the bail. 60

4. A locking closure for containers having a pivotally mounted bail, rollers at the lower ends of the bail, locking members including wedge-shaped guides at the sides of the container adapted to receive the rollers on the ends of said bail and to frictionally grip the rollers and hold the bail in depressed position, thereby retaining 70

the cover in locked position upon the container, and a positive locking means carried by the cover of the container engaging the bail in either the uppermost or lowermost position of said bail.

5. A locking closure for containers having a pivotally mounted bail, rollers at the lower ends of the bail, locking members including wedge-shaped guides at the sides of the container adapted to receive the rollers on the ends of said bail and to frictionally grip the rollers and hold the bail in depressed position, thereby retaining the cover in locked position upon the container, a positive locking means carried by the cover of the container engaging the bail, said locking means including a laterally movable latch, and means on the cover adapted to withdraw said latch, said bail having a notch adapted to be engaged by the latch.

6. A locking closure for containers having a pivotally mounted bail, a handle mounted upon the cover of the container, guide members at the sides of the cover through which the vertical side portions of the bail are adapted to pass, a latch member mounted upon the cover and passing through one of said guide members to engage one of the vertical side portions of the bail, and means associated with the handle of the cover for withdrawing the latch from its engagement with the bail.

7. A locking closure for containers having a pivotally mounted bail, tapered housing members mounted at the sides of the container adapted to receive the ends of the bail and hold the cover in place, and means permitting removal of the bail from said members when desired.

8. A locking closure for containers having a pivotally mounted bail, tapered housing members mounted at the sides of the container adapted to receive the ends of the bail and hold the cover in place, and means permitting removal of the bail from said members when desired, said means including cut-away portions at one side of the members whereby the ends of the bail may move laterally inwardly against the natural resiliency of the bail when it is desired to remove the ends of the bail from the members.

9. A locking closure for containers having a pivotally mounted bail, housing members at the sides of the container adapted to receive the ends of the bail whereby it may occupy either an upper or lower position, friction means associated with the bail for holding the bail in its lowermost position in the housings, the closure of said container having a handle, and an auxiliary handle movable relatively thereto, and a latch on the cover cooperating with the bail for positively holding the cover in either of two predetermined relations to the bail as desired.

LOUIS EISENMAN. 30
